UNITED STATES PATENT OFFICE.

FRIEDRICH WILHELM WEBER, OF BOCHUM, GERMANY, ASSIGNOR TO THE FIRM:
VEREINIGTE STAHLWERKE AKTIENGESELLSCHAFT, OF DUSSELDORF, GERMANY.

DEVICE FOR FASTENING RAILS.

Application filed February 9, 1927, Serial No. 166,991, and in Germany February 9, 1926.

The fastening of rails is usually carried out in such a manner, that the foot of the rail is connected to the support by means of clamping wedges and screws.

- 5 The invention has reference to a device in which said mode of connection is replaced by a much simpler one. According to this invention the rails are connected by means of bridges which are either rigidly connected
10 with the sleeper or are formed of the sleeper by being pressed out of it. The bridges serve as support for the proper means of connection, which have, preferably, a wedge-like form. The pieces are pushed under the
15 bridge in such a manner, that they rest upon the foot of the rail and press the foot firmly on to the support.

The bridges or bridles have preferably an inclination according to that of the wedge-shaped pieces. The counterpart of these wedge-shaped pieces may also be pressed out of the sleeper.

An example for a device according to the invention is illustrated on the accompanying
25 drawing.

Figure 1 is a cross-section through a rail connected according to the invention,

Fig. 2 is a side elevation, partly in section,
Fig. 3 is a plan view and

30 Fig. 4 shows the profile of the sleeper.

The bridge-shaped elevations *a* and wedge counterparts *e* are pressed out of the sleeper *d*. The wedges *b* are firmly clamped under said elevations in such a manner that they exert a pressure on the foot *c* of the rail and
35 press the foot against the sleeper.

As shown in Figure 4 the longitudinal axle
40 of the sleeper is provided under the cover with ribs *e*. These ribs serve for furnishing sufficient material for the side walls of the bridges or bridles on being pressed out.

The device has, compared with the hitherto known means of connection, the advantage of greater simplicity in the fabrication of the several parts and in the attendance by those workers who have to carry out the fastening of the rails. But also in respect to the stability the new device is at least equal to those hitherto used. By the arrangement accord-

ing to the invention a weakening of the 50 sleeper is prevented, whereas the sleepers in the former manners of fastening must be punched for the receipt of screws and plates.

It is always possible to provide for a bearing plate between the bridge *a*, the foot *c* of 55 the rail, the sleeper *d* and the wedge *b*, when the distances of the two bridges are chosen accordingly.

The invention may also be used with base- 60 plates. Instead of the bridge-shaped elevations it is also possible to use two hooks, the one of which is directed against the other one.

What I claim and desire to secure by Letters Patent of the United States is:

1. Means for securing railway and like 65 rails to sleepers comprising a bridge rigidly secured to the sleeper at each side of the rails, a wedge-shaped member to be inserted under each bridge, and characterized by the fact that the under side of the bridge, the wedge 70 counterpart embossed on the sleeper and the top face of the rail base constitute a wedge-shaped seat which tapers in a direction away from the rail web, in such a way so that after the rail is placed between said bridges each 75 wedge may be introduced into said seat, the upper surface of said wedge frictionally engaging the under side of the bridge and the lower surface thereof frictionally engaging said rail base and said wedge counterpart. 80

2. Means for securing railway and like rails to sleepers as recited in claim 1 in which each bridge web has an angle of inclination roughly the same as the inclination of the respective upper rail base face turned towards 85 it.

3. Sleeper of the kind characterized in claim 1 in which the bridges are to be pressed out of the sleeper, characterized by the feature that the sleepers on their under side 90 are provided with reinforcement ribs which, in longitudinal direction of the sleeper, extend over the places from which the bridges have been pressed, and which reinforce the sleepers and furnish sufficient material for the 95 pressing-out of the bridges and wedge counterparts without reducing the section.

FRIEDRICH WILHELM WEBER.
